DOMESTIC APPLIANCE

Norman J. Bullock, Dayton, Ohio, assignor to General Motors Corporation, Detroit, Mich., a corporation of Delaware

Filed Sept. 9, 1960, Ser. No. 55,066
1 Claim. (Cl. 210—382)

This invention relates to a domestic appliance and more particularly to an improved clothes guard ring for a spin tub.

In the prior art, some spin tubs having imperforate bottoms and a circumferentially arranged plurality of outflow ports at the top thereof are provided with clothes guard rings which overlie the outflow ports to prevent blockage thereof. One such guard ring is taught in the Patent to Johnston et al. 2,956,684, issued October 18, 1960, and assigned to the same assignee as the instant invention. All the prior art guard rings have been metallic to withstand the stresses involved in a centrifuging device. This relatively rigid construction requires further modification of the ring in order to facilitate installation of the ring within a spin tub. However, in the mass production of laundry appliances, the cost of manufacturing and installing metallic clothes guard rings is considerable and it is to the solution of this adverse cost and other problems that the present invention is directed.

Accordingly, it is an object of this problem to provide an improved moldable clothes guard for a spin basket.

It is another object of this invention to provide a spin basket having outflow ports around an upper portion thereof with a plastic clothes guard ring supported on said basket by integral protuberances which extend into certain of said ports.

A further object of this invention is the provision of a one-piece clothes guard ring which can be installed in a spin basket after the basket is assembled.

Further objects and advantages of the present invention will be apparent from the following description, reference being had to the accompanying drawings wherein preferred embodiments of the present invention are clearly shown.

In the drawings:

FIGURE 1 is a fragmentary sectional view partly in elevation of a clothes washing machine suitable for use with this invention;

FIGURE 2 is a fragmentary sectional view of a spin tub provided with one form of this invention;

FIGURE 3 is a fragmentary sectional view of a spin tub provided with another form of this invention;

FIGURE 4 is a top elevational view of the preferred clothes guard ring of this invention;

FIGURE 5 is a fragmentary view taken along line 5—5 in FIGURE 4;

FIGURE 6 is a sectional view taken along line 6—6 in FIGURE 4; and

FIGURE 7 is a schematic view representing the method of installing the guard ring of this invention.

In accordance with this invention and with reference to FIGURE 1, a fragmentary sectional view of a clothes washer 10 is illustrated. A clothes washer of the type suitable for use with this invention may include a top wall 12 having a recessed shoulder 14 terminating in an access collar or opening 16. A door 18 may be hingedly mounted to the cabinet top 12 for opening and closing the access collar 16 in the clothes washer cabinet. Within the clothes washer 10, a spin tub assembly 20 is rotatably disposed. An agitator 22 is carried inside the tub assembly 20 and an agitating and spinning mechanism 24 is adapted to selectively rotate the tub assembly 20 or vertically reciprocate the agitator 22.

2

The spin tub or basket assembly 20 is comprised of an imperforate tub bottom or water container portion 26, an annular tub rim housing or collar 28, and an annular tub rim 30. The tub rim housing 28 is formed with a depending flange 32 which is welded about its periphery to the upper edge of the tub bottom 26. The tub rim housing 28 also defines the spin tub access opening 34 and a plurality of circumferentially arranged outflow ports 36. Further, the tub rim housing 28 is formed with a bottom shoulder 35 between the access opening collar 34 and the outflow ports 36. In order to form a chamber 38 for receiving a ballast material, such as hematite ore, the tub rim 30 is welded along an upturned annular flange to the collar 34 of the tub rim housing—the lower end of the tub rim being welded to the tub rim housing just above the outflow ports 36.

When the spin tub 20 is rotated, water is centrifuged therefrom by way of the outflow ports 36 into a water container—the sub-top or cover portion 40 of which is seen in FIGURE 1. The sub-top 40 has an upstanding annular radially inner flange for supporting a flexible guard collar or sleeve 42 in axial alignment with the cabinet access collar 16 and the tub access opening collar 34. The flexible collar 42 is positioned closely adjacent the tub access opening 34 to prevent articles of clothing from being flung out of the spin tub into the water container. As the spin tub 20 is rotated, the water will tend to climb the upwardly and outwardly tapered side walls of the tub bottom 26 and will eject through the outflow ports 36. However, where too many clothes are placed within the spin tub 20, certain of the articles may find their way into blocking engagement with the outflow ports 36. If this happens, the clothing acts as a dam and the centrifuged water tends to be thrown out of the tub access opening 34 and into the water container. For this reason, a clothes guard ring shown generally at 44 is positioned on a bias between the shoulder 35 of the tub rim housing and the imperforate tub bottom 26. The ring 44 serves to prevent articles of clothing from blocking the outflow ports 36.

In the prior art, the clothes guard rings 44 were formed of metal or other high stress material in order to withstand the forces of centrifuging. Similarly, the prior art clothes guard rings were formed in a manner which required their installation within the spin tub 20 while the spin tub was being assembled. The aforementioned patent taught one means whereby a jointed guard ring could be positioned within the spin tub after the tub was manufactured. However, the metallic guard ring of the copending application was expensive to manufacture and included a means of locking the disjointed ring together once installed within the spin tub. Both the cost of manufacturing this metal ring and the cost of locking the ends of the ring together were undesirable and a cheaper, more efficient guard ring installation was sought. Further, the prior art metallic rings required a plurality of welding operations wherever the concentric rings were joined together. All this added to the cost of the product in the highly competitive clothes washing machine market. Thus a new type guard ring was conceived in accordance with the teachings of this invention. There was required, first, a guard ring which could be installed simply and quickly within a completed spin tub. Secondly, the guard ring must be inexpensive to manufacture and, thirdly, the guard ring must be able to withstand the temperatures of clothes washing liquids and the pressures and stresses involved in centrifuging.

With reference to FIGURE 2, the guard ring 44 is shown comprised of a one-piece, unitary or integral, molded plastic ring having a radially inner V-shaped ring 50, a radially outer V-shaped ring 52 and an intermediate

V-shaped ring 54. Spaced about the periphery of the concentrically arranged rings 50, 52 and 54 are a plurality of radially directed integral ribs 56. In addition to joining the ribs, the radial connector 56 includes a protuberance or attachment lug 58 which extends into certain of the outflow ports 36 when the ring 44 is installed within the spin tub 20. Note that the innermost ring 50 rests on the shoulder 35 of the tub rim housing 28, thereby forming an annular generally triangularly shaped chamber 60 which is in constant communication with the outflow port 36 of the spin tub. Fabric or articles of clothing are prevented by the ribs 50, 52 and 54 from entering the chamber 60 and blocking the outflow ports 36.

A preferred embodiment of this invention is shown as a clothes guard ring 70, more particularly illustrated in FIGURES 3, 4, 5 and 6. The guard ring 70 is formed of a thermoplastic, such as polypropylene—a plastic resin which does not soften or distort below approximately 250° F. Since the maximum water temperatures within a clothes washer suitable for use with this invention do not exceed 180° F., the selection of polypropylene is considered satisfactory for use with this invention. The clothes guard ring 70 includes a radially inner V-shaped ring 72, a radially outer V-shaped ring 74 and an intermediate V-shaped ring 76, all of which rings are concentric one with the other. Spaced circumferentially about the concentric rings are integral radially directed connector ribs 78 which have an outer mounting or toe portion 80 which interfits with the bottom of an outflow port 36 to hold the ring 70 in proper relationship with the spin tub.

Although one would believe that plastic is wholly incompatible as a guard ring in a centrifuging device where elevated temperatures are incurred, the construction of the guard ring 70 is found to possess all of the attributes necessary for preventing blockage of the tub outflow ports. The guard ring 70 is designed to be moldable in a one-piece construction and thus can be manufactured at extremely low cost. To facilitate the molding and stress requirements of the guard ring 70 (FIGURE 6), the concentric rings 72, 74 and 76 are formed as follows—an explanation in connection with ring 74 serving as a typical example of the other two rings 72 and 76. The ring 74 is formed with a radially outer side wall 84 and a radially inner side wall 86 forming an angle of approximately 90° with the outer wall 84. Thus, the ring configuration is such that an angle A and B are 45° as seen in FIGURE 6. The thickness of the plastic side walls 84 and 86 are $\frac{1}{32}$ of an inch; whereas the width of the connector ribs, such as 78, are $\frac{3}{32}$ of an inch thick. These dimensions are designed to apply to the guard ring 70 which has a dimension C of twenty inches in diameter across the outside ring 74. For strength purposes in a guard ring 70 of the subject design, the intermediate ring 76 should have an outer diameter D of eighteen and three-fourths inches and the radially inner ring 72 should have an outer diameter E of seventeen and one-half inches. In addition to the added strength and molding facility provided by the V-shaped configuration of the concentric rings, each ring should have a width F of approximately $\frac{3}{8}$ inch. The lower tip of the V-shape should be formed with a radius G of $\frac{3}{32}$ of an inch. With the foregoing dimensions, a one-piece guard ring 70 molded of polypropylene plastic will provide all of the strength necessary to withstand the temperature and forces within the spin tub 20.

The simplified molding process for making the guard

ring 70 is as follows. First, the polypropylene chips are retained within a hopper and fed to a melter where they are liquefied. Next, the liquefied plastic is hydraulically fed to a mold for forming the guard ring configuration shown. The mold may be cooled, as by water, to expedite the curing process and, when the mold is opened, the guard ring 70 may be removed as a one-piece integral unit suitable for installation in a completed spin tub.

To install the guard ring 70 in the spin tub 20, reference may be had to FIGURE 7. The flexible or resilient guard ring 70 is simply grasped at opposite points on its periphery and collapsed or deformed into the configuration of FIGURE 7. The guard ring is slipped within the spin basket 20 and allowed to assume or restore to its natural shape with the toe portions 80 of the connector pieces 78 resting on the bottom of their respective outflow ports 36. An upper annular flange 90 on the tub bottom lays in juxtaposition to the outflow ports 36 and serving as an abutment against which the toe piece 80 may terminate. When the ring is snapped into place in the tub, the top of the connector pieces 78 will bear against the shoulder 35 of the tub rim housing 28. The installation is quickly accomplished and a simple low cost guard ring is effected which is able to perform the same task as the much higher stress metallic rings used in the prior art.

While the embodiments of the present invention as herein disclosed, constitute preferred forms, it is to be understood that other forms might be adopted.

What is claimed is as follows:

In combination, a spin basket having a cylindrical, open-end container portion and a tub rim housing portion, said housing portion having an access opening smaller than the diameter of said container portion and a ported flange attached to said open end of said container portion, means for rotating said tub in a centrifuging operation, and a unitary contractible means having a permanently joined circumferential construction comprising a plurality of concentrically arranged continuous, V-shaped rings, and a plurality of integral connector pieces for holding said rings in spaced relationship to each other and to said ported flange, said contractible means having a natural configuration within said basket in front of said ported flange and in interlocking engagement therewith for preventing a substance being centrifuged from blocking said ported flange, said contractible means formed of a plastic such as polypropylene which has a sufficient characteristic of resilience to enable said contractible means to be deformed to an unnatural configuration for passing through said access opening, the deforming of said contractible means effecting a restoring force in said plastic to enable said contractible means to snap to said natural configuration, said integral connector pieces having toe portions extending into said ported flange for effecting said interlocking engagement therewith solely as a result of said restoring force for supporting said contractible means in said spin basket when said contractible means snaps to its natural configuration.
